APPARATUS FOR HOT PRESSING
POWDERED METALS

Lloyd D. Richardson, Sr., Spring Valley, Ohio,
assignor to H-P-M Development Corporation,
Mount Gilead, Ohio, a corporation of Delaware

Substituted for application Serial No. 622,743,
October 17, 1945. This application April 17,
1950, Serial No. 156,418

5 Claims. (Cl. 219—3)

1

This application is a substitute application for my prior forfeited application Serial Number 622,743, filed October 17, 1945, entitled "Method and Apparatus for Hot Pressing."

This invention relates to apparatus for forming workpieces from powdered materials, at least a portion of which is metallic, and particularly refers to the hot forming of such materials.

The usual method of forming workpieces from powdered metals requires that the powdered material first be compacted into the configuration of the workpiece and thereafter heated to sintering temperature in a separate oven. This manner of producing the workpieces requires additional machine work following the sintering because of the shrinkage which takes place in the sintering oven. Also, two complete machines are required, one for shaping the workpiece and the other for sintering.

The principal object of this invention is to provide apparatus in which compacts of the material to be worked are preheated adjacent the pressing station and are continuously fed thereto, whereby completed workpieces result when the heated compact is pressed.

It is a further object of this invention to provide apparatus for hot working briquettes or compacts of granulated materials into workpieces, starting with the cold briquette or compact and finishing with a completed workpiece.

It is still another object to provide apparatus for receiving cold briquettes, and heating the briquettes to working temperature, and for working the heated briquettes into shape, these steps being carried out in a reducing atmosphere.

These and other objects and advantages will become more apparent upon reference to the accompanying drawings, in which:

Fig. 1 is an elevational view showing an apparatus constructed according to this invention;

Fig. 2 is a plan view of the device shown in Fig. 1;

Figs. 3, 4, 5, and 6 are views illustrating the apparatus in various stages during a pressing cycle; and

Figs. 7, 8, 9, and 10 are views of a modified construction in various stages of a pressing cycle.

Referring to the drawings, and particularly to Figs. 1-6, there is illustrated a press comprising a bed 10 which rotatably mounts a turret 12 that is driven in its indexing movements by a motor 14 through the pinion and rack arrangement at 16.

The turret carries a plurality of die cells 18, in this case, four, which are adapted successively

2

to register with a heating station at 20 and thereafter with a pressing station at 22.

Connected with the bed 10 by the strain rods 24 and nuts 26 is a press head 28 which supports the cylinder 30 of the pressing station. The head 28 likewise supports the sleeve 32 of the heating station 20.

As will be seen in Fig. 3, the heating station 20 comprises a sleeve of electrical insulating material about which is arranged a coil 34 which may be selectively connected with a source of high frequency electrical energy 36 by means of a switch 38.

In opposed relationship to the pressing station 22, and on the other side of the turret therefrom, is a motor 40 within which is reciprocable the plunger 42 that forms a bottom for the die cells as they are moved into pressing position and have a workpiece operated therein. The motor 40 is preferably fluid operable and is controlled in its movements by a valve 44.

Reciprocable within the cylinder 30 of the pressing station 22 is a sleeve 46 and a core plunger 48 which are independently actuated for pressing workpieces in the die cells 18. The plungers are preferably fluid operable and may be controlled by any suitable valve means, not shown.

The briquettes or compacts to be worked are indicated at 50 and are placed within the sleeve 32 with the electrically non-conductive spacer discs 52 arranged therebetween. Then, when electrical energy is supplied to the coil 34, the briquettes may be raised to sintering temperature without welding or sticking together.

In order to transfer the compacts to the die cells and to remove the separating discs, there are provided plates 54 and 56, the former of which is reciprocable across the opening of the sleeve 32. The lower plate 56 has an aperture 58 therein of the size to pass a compact but to stop the separating discs. Spaced from the aperture 58 is a second aperture 60 in the plate 56 of a size which will pass the said discs. An aperture 62 in the plate 54 of the same size as the aperture 60 is adapted for receiving one of the discs 52 when the plate 54 is moved into its Fig. 5 position.

Thereafter, the plate 54 is reciprocated into its Fig. 3 position, and the disc 52 drops through the apertures 60 and 62.

It will be apparent that the reciprocation of the plate 54 is effective to feed the compacts into the die cells located under the sleeve 32.

The workpieces are formed within the die cells 18 and around the core plunger 48 by advancing

the sleeve 46 against the plunger 42, which is also hollow to receive the end of the core plunger 48. After the forming pressure has been applied for a sufficient length of time, the plunger 42 is retracted downwardly and the workpiece is ejected by stripping it from the plunger 48 by the sleeve 46.

As a simple means for directing the ejected workpiece to a conveyor or other receiver, there is provided the pivoted chute 64 which pivots into position to receive the eject when the plunger 42 is retracted and which yields before the said plunger when the same is moved into pressing position.

Operation of first embodiment

In operation, a number of briquettes or compacts are placed within the sleeve 32 with the spacers 52 therebetween. Electrical energy is supplied to the coil 34 at such a rate that the compacts will be at sintering temperature when they pass from the lower end of the sleeve 32. A reciprocation of the plate 54 feeds a compact into the adjacent die cell 18.

The turret is then indexed to bring the die cell into alignment with the pressing station and a pressing operation takes place, during which the plate 54 is again reciprocated to feed another briquette into the die cell then in alignment with the sleeve 32.

After the pressing is completed, the workpiece is ejected and the turret indexes again to commence a new cycle.

By continuously supplying briquettes and separators to the upper end of the sleeve 32, the heating coil may be continuously energized in order progressively to heat the compacts to the proper working temperature. The discs between the workpieces prevent the same from sticking together and also assist in trapping gases around the briquettes in order to prevent oxidation thereof while at elevated temperatures.

Second embodiment

In Figs. 7-10, there is shown an apparatus for receiving the compacts or briquettes 70 in a tube 72 and for passing them through a heating chamber, indicated at 74, which is supplied with energy by the induction coil 76.

The compacts are transferred from the sleeve 72 into the chamber 74 and passed through the chamber 74 by a plunger 78 which may be reciprocated by fluid pressure.

The briquettes 70 are ejected from the heating chamber at sintering temperature and are received upon the upper end of a vertically acting transfer plunger 80 which may, like the plunger 78, be reciprocated by fluid pressure.

When the plunger 80 is in its lower position, the briquette carried thereby is aligned with a die 82 and is transferred therein by the simultaneous actuation of the pressing sleeve 84 and core plunger 86. The briquette, when in the die, is compacted between the sleeve 84 and the hollow plunger 88. The pressing sleeve 84 and plunger 88 are preferably fluid operable by suitable hydraulic motor means.

After the compact has been pressed into a workpiece, the plunger 88 is retracted and the sleeve 84 is advanced to push the finished workpiece from the die and onto a conveyor, chute, or other suitable receiver, indicated at 90. At this time, the sleeve 84 moves relative to the plunger 86 to strip the workpiece therefrom.

The heating chamber, transfer plunger, press-

ing station, and workpiece receiver are all enclosed by a chamber 92 which may be supplied with a reducing atmosphere by the pipe 94 and valve 96. The heated briquette is thus continuously blanketed by a controlled atmosphere, and chemical changes therein of an undesirable nature are prevented.

For actuating the sleeve 84 and plunger 88, there may be provided a motor mechanism, generally indicated at 100, which comprises a cylinder 102 having fluid supplied to one end thereof by the conduit 104 and to the other end thereof by the conduit 106. The sleeve 84 is connected with the piston 108 within the cylinder 102, and the plunger 86 is connected with the piston 110. When the plungers are in their Fig 7 position, they may be driven forward simultaneously by a supply of pressure fluid through the conduit 104, the conduit 106 being exhausted at this time. The sleeve and plunger move together throughout their forward stroke until the piston 108 bottoms. When the sleeve and plunger are in their furthest left hand position, the conduit 106 communicates with the space between the pistons 106 and 110 by means of the groove 112. Accordingly, when pressure is supplied to the conduit 106 to retract the pistons 108 and 110, the former is urged leftwardly and the latter rightwardly. When the piston 110 has moved rightwardly a predetermined distance, a lost motion mechanism at 114 causes it to pick up the piston 108 so that thereafter they move rightwardly together. Simultaneously with the picking up of the piston 108 by the piston 110, the bypass conduit 116 permits a supply of fluid from the conduit 106 to the left hand side of the piston 108 in order to assist the initiation of the movement thereof.

The rightward movement of the two pistons continues until the piston 110 bottoms, and thereafter the piston 108 continues rightwardly until it engages the piston 110, the fluid therebetween being discharged through the check valve 118 which opens from the cylinder 102 into the conduit 104.

Operation of second embodiment

In operation, a supply of briquettes is placed in the sleeve 72 and the heating chamber 74, and heat is supplied to the latter by the energization of the coil 76. The briquettes are transferred one at a time from the heating chamber to the pressing station by the plunger 80 to be pressed between the sleeve 84 and the plunger 88.

Briquettes are also supplied to the heating chamber by the plunger 78 from the supply sleeve 72. The energization of the coil 76 may be adjusted so that the briquettes are progressively heated to be at proper sintering temperature when ejected from the heating station.

The above mentioned operations are carried out in a reducing atmosphere supplied to the chamber 92 so that oxidation of the briquettes is prevented and a good quality workpiece results.

It will be apparent that this invention provides means for continuously processing cold briquettes through a heating and a pressing stage into completed workpieces while inhibiting oxidation thereof.

A pressing apparatus embodying the methods of this invention provides for a rapid and economical manner of producing parts from powdered metals.

It will be understood that this invention is susceptible to modification in order to adapt it

to different usages and conditions, and, accordingly, it is desired to comprehend such modifications within this invention as may fall within the scope of the appended claims.

I claim:

1. In an apparatus for hot pressing compacts of powdered metal into workpieces; a pressing station comprising pressing members; a plurality of die means movable in succession into said pressing station; means for supplying hot compacts to said die means, comprising a sleeve through which said compacts are adapted for being passed, and beneath which said die means move toward said pressing station; an induction coil for progressively heating the compacts as they are passed through said sleeve; electrically non-conductive spacer members between the compacts being heated for preventing the welding together thereof in said sleeve; and feeding means operable in unison with the movement of said die means for ejecting said spacer members while permitting a heated compact to drop into each said die means.

2. In an apparatus for hot pressing compacts of powdered metal into workpieces and having a pressing station; means for supplying hot compacts to said pressing station, comprising a sleeve of dielectric material adapted for passing said compacts; dielectric spacer members within said sleeve between said compacts for preventing fusion of said compacts one with the other and for entrapping gases thereabout; electrically energizable means for progressively heating said compacts to sintering temperature within said sleeve; and means operable for feeding the heated compacts one at a time to said pressing station and for ejecting said spacer members.

3. In an apparatus for hot pressing compacts of powdered metal into workpieces and having a pressing station; means for supplying hot compacts to said pressing station, comprising a sleeve of electrically non-conductive material adapted for passing said compacts; electrically non-conductive spacer members within said sleeve between said compacts; an induction coil for progressively heating said compacts to sintering temperature within said sleeve; and means for

ejecting said spacer members while feeding said compacts one at a time to said pressing station.

4. In an apparatus for hot pressing powdered metal compacts into workpieces and having a pressing station with pressing members; a turret mounting a plurality of dies and operable to successively index said dies into said pressing station; means for supplying hot compacts to the die next to be indexed into said pressing station, comprising a vertically arranged passage of electrical insulating material adapted for passing compacts therethrough; electrically non-conductive spacer discs within said passage and between said compacts for preventing the welding together thereof and for entrapping gases thereabout; electrical means for progressively heating the compacts to sintering temperature; and means for ejecting said spacer discs while feeding said compacts to said die.

5. In an apparatus for the hot pressing of powdered metal compacts into workpieces and having a pressing station; a heating station for supplying hot compacts to said pressing station, comprising a vertically arranged sleeve of electrically non-conductive material; an induction coil for heating compacts placed in said sleeve; electrically non-conductive spacer members between the compacts within said sleeve; a first plate adjacent the lower end of said sleeve, having an aperture therein adapted for passing said compacts but for stopping said discs; and a second plate between said first plate and said sleeve, having an aperture therein for receiving said discs, the reciprocation of said second plate being operable to eject a disc and to permit a compact to pass through the aperture of said first plate to said pressing station.

LLOYD D. RICHARDSON, SR.
